BREADBOX

Samuel J. Popeil, Chicago, Ill.

Application March 26, 1951, Serial No. 14,621

Term of patent 14 years

(Cl. D44—5)

To all whom it may concern:

Be it known that I, Samuel J. Popeil, a citizen of the United States, residing at Chicago, in the county of Cook and State of Illinois, have invented a new, original, and ornamental Design for a Breadbox, of which the following is a specification, reference being had to the accompanying drawing, forming a part thereof.

In the accompanying drawing.

Fig. 1 is a front elevational view of a breadbox showing my new design.

Fig. 2 is a side elevational view.

Fig. 3 is a top plan view.

Fig. 4 is a rear elevational view.

Fig. 5 is a perspective view showing the breadbox closed.

Fig. 6 is a perspective view showing the door of the breadbox partially open.

Fig. 7 is a perspective view of the box showing the door fully open.

I claim:

The ornamental design for a breadbox, substantially as shown.

SAMUEL J. POPEIL.
